 Bigelow-Garvey Lumber Co., Chicago, Ill., a
 corporation of Illinois

Application May 25, 1944, Serial No. 537,217

8 Claims. (Cl. 217—48)

1

The present invention relates to an improved and simplified form of a comparatively light weight and strong packing and shipping crate, case or container including a collapsible body and top and bottom members constructed of materials such as corrugated board, cardboard, fiber board and the like, and used in combination with wooden reinforcing cleats and wooden posts to provide a crate or the like which is easy to manufacture, conveniently collapsed for conserving space in storage or shipping, and which may be rapidly assembled without requiring any additional nailing between the side and end walls of the body of the crate and merely necessitating the insertion of the top and bottom walls in place and fastening the same at predetermined locations to the side and end walls of the body.

It is an object of this invention to provide an improved, simplified and strong crate constructed of fiber board and wood and including a collapsible open body section having end walls which are permanently secured to side walls which are formed with a plurality of hinges to facilitate collapsing of the body section with the hinges disposed within the body section both in a collapsed and in the setup form of the crate body section to protect the hinges and increase the life and usefulness of the crate.

It is also an object of this invention to provide an improved collapsible type of crate wherein the collapsible body section is provided with inside hinges and wherein the end walls are permanently nailed to the side walls without interfering with the collapsing or setting up of the crate body section.

It is a further object of this invention to provide an improved light weight and strong collapsible crate or container wherein two opposite walls of the housing or body are provided with a plurality of hinge portions and with integral reinforcing means which also reinforce the hinge portions and provide rounded guide edges to facilitate placement of the top and bottom members in the body of the crate.

It is furthermore an object of this invention to provide an improved combination fiber board and wood crate of the collapsible type wherein a body section has the wooden members of two opposite walls thereof permanently nailed or otherwise secured to wooden members of the two connecting walls without interfering with the collapsing or the setting up of the body section thereby affording an arrangement whereby the user of the crate does not have to nail the body walls together

2

when the crate is set up for use for the reception of the top and bottoms walls of the crate.

Still another object of the invention resides in the provision of an improved collapsible type of crate embodying a body section open at the top and bottom and including two opposite side walls to which the end walls are permanently secured, with each of the side walls including side and intermediate hinge portions which are disposed on the inside of the crate body section to protect the same both in the collapsed and in the setup form of the body section.

Another object of the invention is to provide an improved collapsible type of combination fiber board and wood crate or the like consisting of top and bottom members and a collapsible body section wherein the end wall cleats are permanently secured to the side wall posts without interfering with the collapsing or setting up of the body section, and wherein the end wall cleats and side wall posts are provided with pre-formed nail holes to facilitate nailing of the body section to the top and bottom members to provide a crate wherein the corners are all of the three-way construction and wherein the top and bottom members when in position press against and protect hinge portions forming part of the body section side walls.

A feature of the invention is to provide a collapsible shipping crate or the like including a collapsible body section wherein the end walls and side walls are rigidly fastened together by nailing the end wall cleats to hinged side wall posts without interfering with the operation of the side wall hinge portions to afford a crate construction eliminating the necessity of the nailing of the end walls and side walls by the user of the crate when the crate is set up for use.

Another important feature of the invention is the construction of a collapsible type of crate including a body section having two opposite walls formed with a plurality of hinge portions and with integral reinforcing strips which not only reinforce the hinge portions but also afford rounded guides to facilitate the rapid and convenient insertion of the top and bottom members in the crate body section.

Another object of the invention is the construction of a container composed of a plurality of elements, one of which is collapsible and includes four walls which are rigidly secured together with two of said walls being collapsible and including a plurality of hinge portions and integral reinforcing strips whereby the container may be conveniently collapsed into a flat condition for stor-

age or shipment, and wherein the reinforcing strips of said two walls afford guides for the easy placement of the top and bottom elements of the container.

It is an important object of this invention to provide an improved and simplified strong type of shipping and packing container including top and bottom elements and a body element, with said body element having the walls thereof rigidly secured to one another with two of said walls being provided with hinge portions adapted to be positioned on the interior of the body element in its collapsed and also in its setup position, said two walls also having integral reinforcing portions affording guides for the top and bottom elements to ease the insertion thereof and permitting the use of preformed nail receiving holes in the body element, thereby obviating splitting or destructive nailing of parts and producing a structure which is simple, light and of sturdy construction and reinforced against tearing of the hinge walls.

Other and further important objects of the invention will be apparent from the disclosures in the specification and the accompanying drawings.

The invention, in preferred forms, is illustrated in the drawings and hereinafter more fully described.

In the drawings:

Figure 1 is a perspective view of the crate showing the crate elements in their relative separated positions for assembly;

Figure 2 is an enlarged vertical sectional view through the collapsible body element taken on line II—II of Figure 1;

Figure 3 is an enlarged vertical sectional view through the body element taken on line III—III of Figure 1;

Figure 4 is a top plan view of the body element in its completely collapsed position illustrating the protected positions of the double hinge portions of the side walls and the guarded positions of the single hinge members of the side walls by corner posts of the body element;

Figure 5 is an enlarged perspective view of a three-way corner construction of the crate with the cover in position and illustrating the positions of the nails engaged in the preformed openings in the body element cleats and posts for rigidly securing the cover in place;

Figure 6 is a fragmentary bottom plan view of substantially one-half of the body element of the crate showing one of the reinforced fiber board side walls partly collapsed and indicating the two hinged portions in one side of the side wall and the single hinge portion in the opposite side of the side wall;

Figure 7 is an enlarged fragmentary perspective bottom view of a corner of the crate body element showing the right angle positioning of the end and side walls with respect to one another in a setup position of the body element and indicating in dotted lines the position of the side wall with respect to the end wall when the body element is collapsed;

Figure 8 is a perspective view of a modified form of crate body element wherein two opposed walls are constructed of fiber board reinforced with wood posts with said side walls being rigidly connected to one another by open type wooden end walls, the members of which are permanently nailed to the hinged corner posts of the side walls without interference with the proper operation of the hinge portions forming part of

the side walls and facilitating collapsing of the body element into a compact form similar to that illustrated in Figure 4.

As shown in the drawings:

5 The improved crate or container of the type illustrated in Figures 1 to 7, inclusive, is of a three element construction comprising separate top and bottom elements and a collapsible body element for interfitting engagement with the top and bottom elements. The crate or container is constructed of a combination of materials, preferably fibrous material such as corrugated board, cardboard, fiber board and the like, combined with wooden cleats and posts to provide an exceedingly strong and rigid construction to withstand wear and tear and prevent distortion.

10 In the selected form of the crate illustrated in Figures 1 to 7 inclusive, the top or cover element comprises a top panel or cover 1 constructed of fiber board or the like and having rigidly secured to the bottom or inner surface thereof a pair of spaced parallel inner wooden cleats 2 which are positioned adjacent to two opposite edges of the top panel 1 and extend so that the ends thereof terminate at the two other edges of the top panel. 15 In large sized crates, if required the top or cover may be provided with intermediate cleats on the top and bottom surfaces, for reinforcing purposes.

20 30 Rigidly secured upon the top face of the top panel or cover 1 and to the inside cleats 2 is a pair of spaced parallel upper or top cleats 3 which are preferably constructed of wood and are disposed at right angles with respect to the inside 35 cleats 2. The outside cleats 3 are longer than the top panel 1 and, as clearly shown in Figure 1 of the drawings, extend beyond both ends of the top panel to facilitate the proper mounting of the top or cover element as hereinafter more fully described.

40 The bottom element of the crate or container, as clearly illustrated in Figure 1, comprises an all-wood open structure consisting of a pair of spaced parallel bottom cleats 4 which are rigidly connected by two transverse inner wooden cleats or bars 5 and by a diagonal cleat or bar 6 which serves as a reinforcing element for the bottom frame constructed of the cleats 4 and 5. While the bottom or lower element of the crate has been 45 described as of an open all-wood construction, it is, of course, to be understood that a bottom may be used constructed similar to the top element formed of the parts 1, 2 and 3 hereinbefore described.

50 55 The top and bottom elements as described are adapted to be used in combination with a collapsible type of body element which is clearly illustrated as the middle unit in Figure 1 and which consists of two identically constructed side walls indicated as a whole by the letter A and connected by means of two identically constructed end walls indicated by the letter B.

60 65 Each of the end wall units B comprises an end panel or wall 7 constructed of fiber board or other suitable material, reinforced by an outer top cleat 8, a bottom cleat 9 and an intermediate cleat 10 all constructed of wood. Both the top and bottom end wall cleats 8 and 9 are provided with preformed nail holes 11. The end wall cleats 8, 9 and 10 are arranged in spaced parallel relationship horizontally on the outer face of an end wall panel 7 and are rigidly secured thereto by means of glue and, or, staples 12 or any other suitable fastening means.

70 75 Connecting the two body element end walls B

are the two side walls A. Each of the side walls A comprises a side panel or wall 13 constructed of fiber board or the like, and having the top and bottom margins thereof bent inwardly against the inner face of the side panel to form an upper side wall reinforcing strip 14 and a lower side wall reinforcing strip 15 as clearly illustrated in Figures 2 and 3. The side wall reinforcing strips 14 and 15 provide upper and lower rounded guide edges 16. Each of the fiber board side panels or walls 13 has the outer face thereof near one end of the panel scored at 17 and 18 transversely of the panel to form a pair of parallel inner hinge sections 19 and 20, thereby providing one side of each of the side panels or walls 13 with a hinged side flange 21 and an intermediate or connecting strip 22 as clearly illustrated in Figure 6. The outer face of the opposite side of each of the side panels or walls 13 is provided with a transverse scoring 23 to form a third inner hinge section 24 which provides a second hinged side flange 25. It will thus be noted that each of the fiber board side walls is constructed of a main panel 13 which is formed with the upper and lower reinforcing strips 14 and 15 and with the scorings 17, 18 and 23 thereby dividing each of the side panels into two hinged side flanges 21 and 25, a connecting section 22 and the main portion of section 13 whereby each of the side wall panels may be collapsed along the hinge sections 19, 20 and 24, as illustrated in Figure 6.

Each of the fiber board side wall units is reinforced by means of an intermediate wooden post or strip 26 which is secured to the outer face of the side wall panel 13 between a pair of corner posts 27 and 28, also constructed of wood or other suitable selected material. The intermediate post 26 is nailed or otherwise secured to the outer face of the side wall 13 and extends from the top to the bottom of said wall with the back of the intermediate post 26 seated tightly against the wall 13. This, however, is not true with respect to the two corner posts 27 and 28 which are hingedly supported by having side faces thereof secured to the flanges 21 and 25 leaving the backs of said posts normally free until the top and bottom elements are nailed in place.

The novel connections between the end walls and side walls of the body section are clearly illustrated in Figures 1 and 5. In the assembly of the body section it will be noted that the hinged end flange 21 of a side wall 13 projects between the outer side face of a corner post 27 and the side margin of the inner face of an end wall panel 7, after which the ends of the end wall cleats 8, 9 and 10 are secured rigidly to the side wall flange 21 and to the outer side of the side wall corner post 27 by nails 29 or other suitable means. This construction permits the free operation or hinged movement of the side wall hinge sections 19 and 20 to permit the double hinge side section of a side wall 13 to be folded around a corner post 27 as illustrated in the collapsed view of the container body section shown in Figure 4. In a similar manner the opposite side wall hinged flange 25 projects between the opposite end wall panel 7 and the outer side of the corner post 28 and is secured rigidly in place by means of nails 29 which engage through the ends of the end wall cleats 8, 9, and 10 through the side wall flange 25 and into a corner post 28.

The novel permanent connection between the body section rigid end walls and the collapsible side walls is more clearly illustrated in the bottom view shown in Figure 6 which clearly illustrates

that the end walls are rigidly secured to the outer sides of the hingedly supported side wall corner posts without interfering with the operation of the three hinge sections forming a part of each of the side walls of the crate body section. This novel arrangement of permanently securing the ends of the end wall cleats and also the end margins of the side wall panels 7, by means of the nails 29, to the side wall corner posts 27 and 28 obviates the necessity of a person when setting up the crate to do any extra nailing of the end walls to the side walls in the improved type of crate. The pre-fastening of the end walls to the side wall corner posts and the side wall side flanges, positions the various hinge sections on the interior of the crate body section in its erected position and permits rapid collapsing of the crate body section into the compact form illustrated in Figure 4, wherein the hinge sections 19 and 20 of each of the side walls are clearly enclosed and protected and wherein the hinge sections 24 are disposed adjacent the inner sides of the end walls 7 and at the innermost corners of the side wall corner posts 28, which consequently serve to protect the hinge sections 24 from injury in the collapsed position of the crate body section.

By referring to Figures 1, 2 and 3 it will be noted that the upper and lower edges of the side walls project beyond the top and bottom edges 30 of the end walls so that the reinforced upper and lower edges of the side walls and the rounded edges 16 thereof afford guides to facilitate the easy insertion of the crate cover and bottom elements in the body element.

35 In the form of crate illustrated in Figure 1 it sometimes is customary to place the bottom unit on a floor and then secure the article to be shipped upon the cleats 5 and 6 to which the article to be shipped may be secured if necessary. 40 With the article positioned on the bottom, the collapsible type body element is opened up into the shape illustrated in the middle view of Figure 1, and the bottom of the body element is then engaged over the article and onto the bottom 45 with the projecting ends of the bottom cleats 4 contacting the lower surfaces of the end wall bottom cleats 9. With the body element in place as described the cover is then placed upon the top of the body element and is guided easily into 50 seated interfitting relationship with the body element by sliding over the rounded guide edges 16 of the side walls with the projecting ends of the top outer cleats 3 seating upon the top edges of the end wall top cleats 8, as clearly illustrated in the 55 enlarged sectional fragmentary view shown in Figure 5.

In the assembling of crates and boxes, of the type herein described, it is necessary to secure the top and bottom members rigidly to the body element. To aid in this assembly the upper and lower ends of the side wall posts 26, 27 and 28 are also provided with nail holes 11. It will thus be noted that with the nail holes 11 provided in the end wall cleats 8 and 9 and in the ends of the 60 side wall posts, that a person assembling and closing the crate or container has only to insert nails 29 into the pre-formed openings 11 and then drive the nails into position to engage the wooden cleats of the top and bottom members to provide a compact sturdy crate all the corners of which are of three-way rigid construction.

In the improved combination fiber board and wood crate or container illustrated and described, it will be noted that the hinge sections 75 forming parts of the side walls of the body sec-

tion are enclosed within the body section and are amply protected both in the setup position of the body section and in the collapsed position thereof. It will also be noted that the upper and lower ends of the hinge sections of the side walls are reinforced by means of the upper and lower reinforcing strips 14 and 15 which are also formed with hinge sections thereby providing double hinge portions. The strips 14 and 15 which form integral parts of the side walls also provide adequate round guide edges for the easy insertion of the top and bottom members into the body section when the same is opened up.

The provision of the pre-formed holes 11 in the end and side walls permits an amateur or an inexperienced assembler to properly position the nails so that the top and bottom sections may be nailed into position without danger of causing splitting of the wooden members forming parts of the top and bottom members of the crate. A decided advantage in the crate is the novel arrangement whereby the end walls are rigidly pre-nailed to the side wall corner posts and side wall side flanges so that when it is desired to assemble the crate it is not necessary for the user to nail the end walls and side walls together as is the usual practice in crates and containers now in use.

In the improved box or crate it will thus be noted that the only nailing which is required by a customer or person using the crate is the insertion of the nails in the pre-formed nail openings 11 of the end and side walls and drive the nails into place in order to hold the top and bottom members rigidly in position and braced tightly against the inner faces of the reinforcing strips 14 and 15 of the side wall members and against the upper and lower ends of the various double thickness hinge sections forming parts of the side walls. The reinforcing strips 14 and 15 which form integral parts of the side walls provide an additional advantage in that they not only reinforce and brace the upper and lower margins of the side walls but they also serve as guides and act as means for preventing the side walls from being torn upwardly or downwardly between the posts.

While the collapsible type of crate illustrated in Figures 1 to 7 inclusive is shown as being substantially square, it will of course be understood that in the production of crates of this type the side walls are usually longer than the end walls. If occasion demands, the end walls may be longer than the side walls. A convenient and rapid compact collapsing of the crate for shipment or storage is not interfered with by any of the dimensional changes of the end and side wall members.

Referring to Figure 8 a modified form of a crate body section is illustrated. In this modified form of a body section the two side wall units are substantially the same as those described and illustrated in Figure 1 and the top and bottom members may also be the same as those shown in Figure 1. If a substantially open crate is desired both the top and bottom members of the modified form of crate may be constructed similar to the bottom member shown in Figure 1. In the modified form of crate body which is of the open type the end wall units are of open construction and each consists of a top cleat 30, a bottom cleat 31 and two diagonally crossed intermediate cleats 32. The ends of the end wall cleats 30, 31 and 32 are nailed to the side wall side flanges 21 and 25 and into the outer sides of the side wall cor-

ner posts 27 and 28. This rigid and permanent connection of the ends of the end wall members to the hingedly supported corner posts of the side walls does not interfere with the operation of the side and intermediate hinge sections of the side walls so that the modified form of crate body section may be conveniently collapsed into compact form similar to that illustrated in Figure 4 for shipment or storage.

When the crate body section is collapsed as shown in Figure 4 the top and bottom members may be placed diagonally in the spaces formed above and below the respective collapsed half portions of the body section. As in the form of crate shown in Figure 1, the modified crate illustrated in Figure 8 is also provided with pre-formed nail holes in the upper and lower end wall cleats 30 and 31 and in the upper and lower ends of the side wall posts so that the only nailing that is required by a person using or setting up the crate is to insert nails in the holes 11 and drive the nails into the respective cleats of the top and bottom members to complete the assembly of a compact and rigid crate, all of the corners of which are of three-way rigid construction.

While the double scoring of each side wall 13 is associated with the side of the side wall connected between a corner post 27 and one side of an end wall of the crate, it will of course be understood that the double scoring may be provided at the opposite side of a side wall 13 for coaction with the corner post 28 so that the body section of the crate may be collapsed by pushing the two corner posts 28 inwardly toward one another instead of the posts 27 as illustrated in Figure 4.

If desired, the side walls 13 may have double scoring at both sides thereof thereby dividing each of the side wall panels into a main panel section, two hinged end flanges and two connecting strips between the end flanges and the main body portion of the panel. This arrangement will permit the body section to be collapsed by moving either the posts 27 or the posts 28 inwardly toward the center.

While the side walls 13 are shown and described as having a single intermediate post 26, it is to be understood that additional reinforcing posts 26 may be provided when necessary. This also holds true for the end walls where additional reinforcing strips or cleats 10 may be used to reinforce the end walls to obviate distortion of the crates. Attention is directed to the use of nails for securing the top and bottom members in the body section of the crate, with the use of the pre-formed nail holes 11. Screws or other suitable fastening means may be used in place of nails if desired. In a similar manner the end wall panels may be secured to the end wall cleats by nails, screws, glue or other fastening means instead of the staples 12.

It will of course be understood that various other details of construction may be varied through a wide range without departing from the principles of this invention and it is, therefore, not the purpose to limit the patent granted herein otherwise than necessitated by the scope of the appended claims.

I claim as my invention:

1. A crate structure comprising three units completely pre-formed for subsequent assembly comprising top and bottom closure units including cleats suitable for receiving nails, and a collapsible body unit for receiving the top and bot-

tom units, said body unit comprising side walls and end walls, said side walls including fibrous panels having combination reinforcing and guide means formed thereon for the easy placement of the top and bottom units in the body unit, said side wall panels, scored to provide a plurality of side and intermediate hinge means disposed on the interior of the body unit and also forming side flanges, posts freely engaged against the exterior faces of the side wall panels and having the panel flanges contacting the side faces of said posts adjacent the end walls, said end walls permanently secured to the side wall panel flanges and to the side wall posts in a manner permitting operation of the side wall hinge means, said end and side walls having pre-formed openings therein for the reception and predetermined placement of securing means to engage in the top and bottom unit cleats to complete the crate assembly.

2. A crate structure consisting of three pre-formed units comprising two end closure units and a collapsible body unit for receiving the same, said body unit comprising two end walls including reinforcing cleats, and two side walls each consisting of an exteriorly scored fibrous panel to form side and intermediate hinge means positioned on the interior of the body unit and also providing side flanges on the panel, corner posts forming parts of each side wall and separated from the end walls by the side wall panel flanges, said end wall cleats rigidly secured to the side wall panel flanges and to the corner posts and permitting operation of the hinge means for collapsing and setting up of the body unit.

3. In a crate of the class described including in addition to top and bottom units a collapsible body unit comprising a pair of end walls, and a pair of side walls, each of said side walls consisting of a fibrous material panel provided with side and intermediate scorings in the outer face thereof forming two side and one intermediate hinge means on the inner side of the panel and also forming two side flanges and an intermediate strip on each panel, each of said side walls also including corner posts having sides which seat against and are permanently secured to the panel flanges and to the sides of the end walls in a manner permitting operation of the hinge means and collapsing of the body unit, said body unit construction being such as to eliminate any further securing of the body unit side and end walls together upon assembly of the top and bottom units with the body unit and only requiring fastening of the body unit to the top and bottom units.

4. In a crate of the class described including a collapsible body unit comprising a pair of rigid walls and a pair of hinge walls permanently secured thereto, each of said hinge walls comprising a fibrous material panel having two side and an intermediate parallel scoring in the outer face thereof forming two side and an intermediate hinge means on the inner face of the panel and also forming side flanges on the panel remote from the intermediate hinge means, reinforcing means secured to the outer face of each panel, corner posts for each panel positioned with surfaces of the corner posts having free contact with the outer face of the panel, said corner posts having other surfaces thereof contacting the panel flanges and permanently secured thereto and to the sides of the rigid walls and permitting oper-

ation of the hinge means in the collapsing and setting up of the body unit.

5. In a crate, a collapsible body unit comprising a pair of side walls each comprising a fibrous material panel having the upper and lower margins thereof bent inwardly against the inner face of the panel to provide reinforcing strips and provide rounded protective edges at the top and bottom of the panel, each of said panels provided with spaced side and intermediate scorings in the outer face thereof to form side and intermediate hinge means on the inner side of the panel and also form end flanges spaced from the intermediate hinge means, reinforcing means secured to the outer face of each panel, corner posts for each panel, each post having one side thereof rigidly secured to a panel flange and leaving the remaining sides of each post free, and end wall forming members having the sides thereof rigidly secured to the side wall corner posts and to the side wall panel flanges in a manner permitting operation of the side wall hinge means in the setting up and the collapsing of the crate body unit.

25 6. In a three unit crate assembly, a body unit comprising a pair of rigid walls and a pair of connecting walls, each of said connecting walls including corner posts and a panel having end flanges rigidly secured between the corner posts and sides of the rigid walls, each of said connecting wall panels formed with two side hinge portions and an intermediate hinge portion to facilitate collapsing of the connecting wall panels for positioning between the rigid walls when the body unit is collapsed.

30 7. In a three unit crate assembly including top and bottom members and a collapsible body unit, said body unit comprising a pair of rigid walls and a pair of connecting walls rigidly and permanently secured thereto to permit collapsing and obviating the need of any additional securing means when the body unit is set up for use, each of said connecting walls including corner posts and a panel having side flanges rigidly secured between the corner posts and sides of the rigid walls, each of said panels also having the top and bottom margins provided with reinforcing strips and guide means projecting above and below the rigid walls for the easy insertion of the top and bottom members into interfitting closing engagement with the body unit, said connecting wall panels each being formed with a plurality of side hinge portions and an intermediate hinge portion on the inner side thereof to facilitate collapsing of the connecting walls for positioning between the rigid walls when the body unit is collapsed for shipment or storage.

35 8. A collapsible container comprising rigid top and bottom members and a collapsible body for receiving the same, said body member comprising inwardly collapsible integrally reinforced side walls each consisting of a pair of side flanges, a main wall section connected to one of said side flanges, and an intermediate strip connecting the main wall section with the second side flange, said side walls also including corner posts rigidly and permanently secured to the side margins of a pair of rigid end walls of the body member and permitting collapsing of the body member, the side flanges being secured between the corner posts and the respective end walls with their free edges extending outwardly.

SIMON J. JOHNSON.
